CONSTANT FACTOR MECHANISM

Oscar W. Swanson and Ernest O. Mossberg, West Hartford, Conn., assignors to Underwood Corporation, New York, N. Y., a corporation of Delaware

Application September 1, 1950, Serial No. 182,672

14 Claims. (Cl. 235—145)

1

This invention relates to printing calculating machines and more particularly to a device to permit retention of a constant factor in the value set-up mechanism for a plurality of computations involving the constant factor.

One object of this invention is the provision in a printing machine capable of addition, subtraction, multiplication and division operations of a mechanism settable to retain a factor set-up by the keyboard in the entry devices for use in a number of distinct multiplication calculations.

Another object is to provide in a printing multiplying machine a factor set-up device in which the factor may be retained for a number of operations and wherein no resetting of such device is required for a total taking operation.

A further object is the provision in such a machine of a factor set-up mechanism and a mechanism operable by the operator to re-index a set-up factor into a controlling position at any desired time.

A still further object of this invention is the design of a factor set-up mechanism for a printing calculating machine in which a factor may be retained by the use of a locking-in mechanism but which set-up mechanism is shiftable to an ineffective position to permit other machine operations.

Still another object is the provision of a factor set-up mechanism which may be set to retain a selected constant factor but shiftable out of effective position to permit machine operations to be performed which do not involve the set-up factor and which may be re-indexed to effective position by operation of a constant key.

Other incidental objects will be in part apparent and in part specifically pointed out in the following detailed description of a preferred embodiment of the invention.

The present invention is an improvement on the mechanism shown in the co-pending application Serial No. 170,968 filed June 29, 1950 by Oscar J. Sundstrand. For this reason only so much of the structure as is required to set out the novel features of the invention is set out herein, reference being made to the above Sundstrand application for a more complete disclosure of the machine involved.

In the drawings:

Figure 1 is a perspective showing of the constant factor set-up mechanism,

Figure 2 is a view from the right side of the pin setting and constant mechanism,

Figure 3 is a top view, partly in section, of the constant re-indexing mechanism.

2

General description

The present invention as disclosed is embodied in an Underwood Sundstrand printing calculator similar to that described in the Sundstrand application above, wherein it is particularly useful for multiplication calculations involving a constant multiplicand. This device is, however, also useful for multiplication in an adding-subtracting machine without the automatic multiplying features of the above application and is not restricted to use in a machine having such automatic multiplication features.

The disclosure herein is of a part of the well-known Underwood Sundstrand calculating machine, further disclosure being deemed unnecessary, for such machine is readily available commercially and fully disclosed in U. S. Patents including among others the following patents issued to Oscar J. Sundstrand: Patent No. 1,583,102, issued May 4, 1926, No. 1,885,489, issued Nov. 1, 1932, and No. 1,965,611, issued July 10, 1934. Such machines comprise a 10 key keyboard operable to set pins corresponding to a value in a set of stationary pins, the pin setting members and a set of read-out members being shiftable across the field of such pins to change the denominational relationship in the usual manner.

The read-out members are connected to a set of type bars cyclically operated to read out and print the set-up values and carrying a pair of racks which are selectively engageable on the return of the type bars by a register to enter the set-up values in the register.

The register is also engageable with the racks following a non-entry cycle, on the forward stroke of the type bars to control the type bars to print the total in the register. During such a total taking operation, the read-out members must be set to a position to the side of the field of pins to prevent any interference with the rise of the type bars from any set pins and heretofore this has resulted in resetting all set pins. It has not been possible in these prior machines to retain an amount set up on the pins during a total taking operation.

The present invention provides means wherein an amount set up in the field of pins may be retained during a total taking operation and a constant key operable to shift the read-out members back into effective position with respect to the pins.

Entry of a constant factor

Entry of a factor which is to be kept available in the pins is performed in the same manner in

this machine as in the prior machines of this type with the exception that all available digital positions must be indexed. This requires that the factor be indexed in the highest denominational position by entering a number of "0's" following the constant or if the constant factor is to be positioned below the highest order, by first entering a number of "0's" into the higher unused orders.

Referring to Figures 1, 2 and 3, a number of numeral keys 10 are connected to a like number of push rods 11 mounted on a swinging gate 12, the rear ends of the rods 11 resting adjacent one vertical line of a stationary field of settable pins 13. The gate 12 is spring urged to the right, Figure 3, and is retained against the urge of its spring by the engagement of a notched arcuate plate 14 with an upper end 15 of gate 12. Upon depression of any key 10 to set through its associated push rod 11, the pin 13 to the rear of rod 11, an escapement push rod 16 is also operated to thrust against plate 14 and move it rearwardly to free end 15 of gate 12. The gate 12 then moves to the right until the end of push rod 16 strikes against the side of the adjacent notch of plate 14 and when the operated key 10 is released, rod 16 is retracted and gate 12 moved to engage the side of the next notch of plate 14, positioning the push rods 11 in line with the next vertical row of pins 13 in readiness for entry of the next digit.

Notched plate 14 is positioned on a stationary stud 19 at its left end and carries a lever 20 pivoted thereon at 21. Lever 20 passes in front of end 15 of gate 12 and is bent around at its right end to engage a pin 22 on plate 14 to limit the movement of plate 14 to prevent any undesired escapement movement of gate 12 under impetus of a hard depression of one of the keys 10. A spring 23 connected to the left end of lever 20 serves to hold both plate 14 and lever 20 in engagement with end 15 of gate 12.

A stud 25, Figure 2, on the rear end of gate 12 is engaged in a slot of a carriage 26 slidable on a shaft 27 to move carriage 26 synchronously with gate 12. A plurality of read-out rods 28 slidably carried by carriage 26 are moved thereby into position to engage the set pins 13. These read-out rods are connected as in the aforementioned patents, to the usual type bars, not shown, to control the values printed and entered into the register in accordance with the settings of pins 13. A slotted pin restoring bar 29 is slidably mounted on the right end of carriage 26 to restore any set pins 13 to unset position as the carriage 26 moves to the left by power at the end of any machine cycle.

The position of gate 12 at any time is indicated to the operator by movement of an indicator arm 30 movable behind slots in the machine casing. Indicator arm 30 is fixed to a slideable rack 31 connected by a pinion 32 having a fixed pivot 33 to a rack 34 fixed to end 15 of gate 12.

Locking in a constant factor

After keys 10 have been operated to enter the desired factor and position swinging gate 12 to its rightmost position, the factor so set in may be retained on pins 13 for subsequent cycles. Movement of gate 12 to its right hand position releases, by an ear 37 on rack 34 fixed to gate 12, a lock 38 for a constant slide 39. Lock 38 is movable sidewise on a shaft 40 and is normally urged by a spring 41 between latch 38 and slide 39 to position a turned down ear 42 on lock

38 in a slot 43 of slide 39. The left end of lock 38 is bent down into the path of ear 37 of rack 34 and when rack 34 moves into the last denominational position of gate 12, ear 37 moves latch 38 to move ear 42 of latch 38 out of slot 43 of slide 39 and free slide 39.

Slide 39 is slidable on shaft 40 and a stud 44 and is moved by a lever 45 pivoted on a fixed stud 46 and provided with a slot 47 embracing a stud 48 on slide 39. In the normal rearward position of slide 39, the set up values on pins 13 are destroyed by bar 29 every time gate 12 and carriage 26 are returned to their home position. When lever 45 is moved to the front of the machine, bar 29 is shifted to align the slots 49 or bar 29 with pins 13 and restoration of gate 12 and carriage 26 will not restore the set pins 13. Slide 39 is provided with a slotted extension 53 which engages a pin 54 of an arm 55 pivoted at 56 on the machine frame. The rear end of arm 55 is slotted to engage, when carriage 26 is in its rightmost position, an ear 57 fixed to the lower end of bar 29. Forward movement of slide 39 will rock arm 55 counterclockwise, Figure 2, to raise bar 29 to its upper position, a detent arm 58 pivoted on carriage 26 serving to retain bar 29 in either set position. An ear 59 on the upper end of bar 29 is positioned either above or below a lower rail of a fixed channel bar 60 at all positions of carriage 26 except the fully indexed position to prevent any undesired shift of bar 29. In summary, when lever 45 is moved to its forward position, bar 29 is shifted to its upper ineffective position and cannot restore the set pins 13 upon return to normal position, hence the factor set up on pins 13 is retained for further use.

Slide 39 is provided with a second slot 60 positioned, when lever 45 is in the forward constant retaining position, adjacent ear 42 of lock 38. 40 When swinging gate 12 and rack 34 move out of the fully indexed position lock 38 is freed to move ear 42 into slot 60. Thus slide 39 and lever 45 are locked in either of their two positions at all times that gate 12 and rack 34 are 45 out of the fully indexed position to prevent any shift of the lever 45, slide 39 and arm 55 without a corresponding shift of slideable bar 29 on carriage 26.

It is also desirable to prevent operation of 50 keys 10 when a constant factor is set up in pins 13 to prevent change in the factor. To this end, use is made of a key lock mechanism present in the standard adding machine. This key lock 55 comprises a plate 62, Figure 2, shiftable forwardly to underlie the bottoms of keys 10 and prevent their depression. Plate 62 is connected to a lever 63 pivoted on a fixed pivot 64 and connected to a link 65 urged rearwardly by a spring 66 to hold plate 62 in an ineffective position.

Normally this plate 62 is moved to key locking 60 position during machine cycling. The main shaft 67 of the machine carries, Figure 1, a roller 68 on an arm 69 fixed to the shaft 67. A second arm 70 free on shaft 67 is connected by a spring 65 71 to press its stud 72 against arm 69. Shortly after shaft 67 starts rotating counterclockwise, stud 72 on arm 70 strikes against a shoulder 73 and moves arm 69 and lock plate 62 forwardly to key locking position. A shoulder 74 on the 70 rear end of arm 69 is moved in this position of the arm 69 in front of a stationary guide 75, spring 66 thereupon moving arm 69 upwardly to latch the arm in its moved position. Upon return of shaft 67 to its Figure 1 position, roller 68 strikes and lowers the rear end of arm 69 to

release shoulder 74 from guide 75 for return of arm 65 and lock plate 62 to unlocking position.

This key locking mechanism is used to lock the keyboard 10 when a constant factor is being retained in the pins 13. A stud 78, Figure 1, on arm 55 is positioned in a slot of a lever 79 pivoted on a fixed stud 80. Also pivoted on stud 80 and connected to lever 79 by a spring 81 is an arm 82, spring 81 urging arm 82 clockwise in Figures 1 and 2 against a screw 83 in lever 79. The lower end of arm 82 rests in back of a stud 84 fixed in arm 65. Through this mechanism, as lever 45 is moved forwardly to retain a constant factor set in pins 13, lever 79 and arm 82 are rocked by arm 55 to move arm 65 forwardly to lock keys 10 against operation.

Reentry of the constant factor

After the constant factor has been locked in as above set out and has been used for the first calculation, swinging gate 12 will generally be positioned at some denominational position other than the fully indexed position and if a total taking operation has been performed, gate 12 will be in the home position. When it is desired to reenter the previously set constant factor, a constant key 90 is operated. This key 90 when operated releases the notch escapement rack 14 for gate 12 to permit movement of gate 12 to the fully indexed position. This movement of gate 12 effects a shift of the read-out pins 23 under pins 13 which have remained set to permit further entries of the factor.

Key 90 is pivoted on the forward arm of a lever 91 pivoted at 92 to the framework for the keyboard, a spring 93 connected to key 90 and a stationary stud 94 serving to maintain key 90 and lever 91 in the normal position. An upper arm of lever 91 is engaged in a hole of an arm of a horizontal lever 95 which carries on its other arm a latch pawl 96 pivotally mounted thereon at 97 and urged by a spring 98 connected between lever 95 and latch pawl 96 to a counterclockwise position, Figures 1 and 3. Counterclockwise movement of latch pawl 96 is limited by engagement of an ear 99 bent down from pawl 96 and the arm of lever 95. Latch pawl 96 holds a slide 100 against rearward movement under the urge of a spring 101 connected to a post 102 on slide 100 and a stationary frame part by the engagement of a shoulder on the rear end of pawl 96 with an ear 103 bent off of slide 100.

Constant key 90 is locked when lever 45 is in its rearward position, that is when no constant is locked into the pins 13, by an ear 104 bent off an upstanding portion of arm 55 resting over the rear end of lever 91. When lever 45 is moved forwardly to retain a set-up constant, arm 55 is rocked to move ear 104 forwardly from above the rear arm of lever 91 and thereby free key 90 for operation. A detent pawl 105 pivoted on pivot 92 for lever 91 is urged upwardly by a spring 106 into engagement with ear 104 and serves to hold lever 45, slide 39 and arm 55 in either set position. Depression of key 90 when it is free rocks lever 91 to rock lever 95 clockwise and withdraw pawl 97 from ear 103 of slide 100. The resulting rearward movement of slide 100 acting through a lever 107 pivoted thereon at 108 and urged clockwise to engagement of its forward arm with post 102 by a spring 109 between slide 100 and lever 107, strikes square stud 21 on escapement plate 14 to move plate 14 rearwardly and free gate 12

for movement to its rightmost fully indexed position, thus in effect re-entering the previously set constant factor.

Rearward movement of slide 100 also acts to 5 reset the conventional hinge blank 110 to prevent a total taking operation. This hinge blank 110 is moved forwardly during a cycle in which swinging gate 12 is in its home position by a stud 111 on a plate 112 fixed to main shaft 67 10 and when blank 110 is so moved, it so controls the machine that the next cycle shall be a total taking cycle. When key 90 is depressed, the next cycle is to be an entering cycle and hinge blank 110 must be restored rearwardly which 15 is done by an extension 113 of slide 100 engaging blank 110 in the rearward movement of slide 100.

Slide 100 is returned to its normal latched condition during the following machine cycle. Upon release of key 90, levers 91 and 95 are 20 restored to their normal positions by spring 93 and pawl 96 engages ear 103 of slide 100, spring 98 yielding to allow return of lever 95. An arm 115 pivoted at 116 to a stationary frame part is tensioned by a spring 117 to hold a roller 118 on the lower end of arm 115 against the left part 119 of slide 100. When slide 100 is freed from pawl 96 and moves rearwardly, it carries arm 115 with it into the path of a stud 119 on plate 112 on the main shaft 67. During the ensuing machine cycle, stud 119 strikes arm 115 and restores slide 100 to normal position wherein pawl 96 moves behind ear 103 on the slide 100 to relatch the slide 100 in its home position.

It has been mentioned that lever 107 is pivotally mounted on slide 100. This is to avoid a possible source of error in operation of the machine. It will be noted that if key 90 is retained depressed or is operated during a machine cycle, slide 100 will be free to move rearwardly during the latter half of the cycle and consequently would free escapement plate 14 from swinging gate 12 after gate 12 had been restored to normal position. To prevent such an erroneous release of gate 12, lever 107 is pivoted on slide 100 45 and has an arm 120, Figure 3, which extends rearwardly into the path of end 15 of gate 12. Then when gate 12 overthrows past its normal home position as it does on every restoration, the end 15 will strike arm 120 to rock lever 107 50 counter-clockwise in Figure 3 and move its rearward arm from square stud 21. This will permit escapement plate 14 to reengage end 15 of swinging gate 12 and retain the gate in its home position even though slide 100 is released.

The above description of a preferred embodiment of the invention is for the purpose of illustrating the invention only and is not to be construed as limiting the scope of the following claims.

60 *What is claimed is:*

1. In a machine of the class described having a set of keys, a field of settable pins, means operable by said keys and shiftable relatively to said pins for enabling operation of said keys to set a multi-digit value in said pins, a member relatively shiftable with respect to said pins to restore any set pins to a non-set position, a normally latched manipulative member, means controlled by said relatively shiftable pin setting 65 means to free said manipulative member from said latched condition and mechanism operated by said manipulative member to move said relatively shiftable member to a non-resetting position with respect to said field of pins.
- 70 2. In a machine of the class described having

a set of keys, a field of settable pins, means operable by said keys and shiftable relatively to said pins for enabling operation of said keys to set a multi-digit value in said pins, a member relatively shiftable with respect to said pins to restore any set pins to a non-set position, a normally latched manipulative member, means controlled by said relatively shiftable pin setting means to free said manipulative member from said latched condition, mechanism operated by said manipulative member to move said relatively shiftable member to a non-resetting position with respect to said field of pins, a cyclically operable locking member to prevent operation of said keys and a connection from said manipulative member to said locking member to move said locking member to locking position when said manipulative member is in one position.

3. In a machine of the class described having a set of keys, a field of settable pins, key operable means shiftable relatively to said field of pins for setting multi-digit values in said pins, a pin restoring member shiftable relatively to said field of pins with said key operable means, a manipulative means operable to shift said pin restoring member to an ineffective position, a latch for said manipulative member and latch releasing means operable in one relative position of said key operated means and said field of pins to release said latch.

4. In a machine of the class described having a set of keys, a field of settable pins, key operable means shiftable relatively to said field of pins for setting multi-digit values in said pins, a pin restoring member shiftable relatively to said field of pins with said key operable means, a manipulative means operable to shift said pin restoring member to an ineffective position, a latch for said manipulative member, latch releasing means operable in one relative position of said key operated means and said field of pins to release said latch, means to lock said keys against depression and a connection from said manipulative means to said key locking means to lock said keys when said pin restoring member is shifted to ineffective position.

5. In an adding machine having a set of numeral keys, a field of settable pins, means relatively shiftable across said field of pins and operable by said numeral keys to set a multi-digit value in said pins, denomination by denomination, a pin restoring member relatively shiftable across said field of pins with said relatively shiftable means, a manipulative means operable to move said pin restoring member across the direction of relative shift of said field of pins and said numeral key operable means to an ineffective position and a detent to hold said pin restoring member in either of its positions.

6. In an adding machine having a set of numeral keys, a field of settable pins, means relatively shiftable across said field of pins and operable by said numeral keys to set a multi-digit value in said pins, denomination by denomination, a pin restoring member relatively shiftable across said field of pins by said relatively shiftable means, a manipulative member connectable to said pin restoring member in one denominational position of said relatively shiftable means and said field of pins and operable to shift said pin restoring member to an ineffective position, and means stationary with respect to said field of pins to prevent shift of said pin restoring member at all times except when said

pin restoring member is connected to said manipulative member.

7. In an adding machine having a set of numeral keys, a field of settable pins, means relatively shiftable across said field of pins and operable by said numeral keys to set a multi-digit value in said pins, denomination by denomination, a pin restoring member relatively shiftable across said field of pins with said relatively shiftable means, a manipulative member connectable to said pin restoring member in one denominational position of said relatively shiftable means and said field of pins and operable to shift said pin restoring member to an ineffective position, means stationary with respect to said field of pins to prevent shift of said pin restoring member at all times except when said pin restoring member is connected to said manipulative member, a latch for said manipulative member and latch releasing means effective only in said one denominational position.

8. In a machine of the class described having a plurality of numeral keys, a group of settable pins, mechanisms, comprising a plurality of actuators and key operable pin setting means, shiftable relatively to said group of settable pins and urged in one direction of relative motion, escapement mechanism to restrain said relatively shiftable mechanisms, said escapement mechanism operable by said keys to enable a one step relative movement of said shiftable mechanisms, a re-indexing key, mechanism operable by said re-indexing key to render said escapement mechanism ineffective and thereby free said relatively shiftable mechanisms for movement to an end position, a pin restoring member relatively shiftable across said group of settable pins with said key operable pin setting means and said actuators, a manipulative member and a linkage operable by said manipulative member and connected to said pin restoring member in said end position of said shiftable mechanisms, to shift said pin resetting member to an ineffective position.

9. In a machine of the class described having a plurality of numeral keys, a group of settable pins, mechanisms, comprising a plurality of actuators and key operable pin setting means shiftable relatively to said group of settable pins and urged in one direction of relative motion, escapement mechanism to restrain said relatively shiftable mechanisms, said escapement mechanism operable by said keys to enable a one step relative movement of said shiftable mechanisms, a re-indexing key, mechanism operable by said re-indexing key to render said escapement mechanism ineffective and thereby free said relatively shiftable mechanisms for movement to an end position, a pin restoring member relatively shiftable across said group of pins with said key operable means and said actuators, a manipulative member, a linkage operable by the manipulative member and connected to said pin restoring member in said end position of said shiftable mechanisms, to shift said pin resetting member to an ineffective position, a latch for said manipulative member, and means on the movable one of said relatively shiftable mechanisms to release said latch when said relatively shiftable mechanisms are in the final position.

10. In a machine of the class described having a plurality of numeral keys, a group of settable pins, mechanisms, comprising a plurality of actuators and key operable pin setting means, shiftable relatively to said group of settable pins

and urged in one direction of relative motion, escapement mechanism to restrain said relatively shiftable mechanisms, said escapement mechanism operable by said keys to enable a one step relative movement of said shiftable mechanisms, a re-indexing key, mechanism operable by said re-indexing key to render said escapement mechanism ineffective and thereby free said relatively shiftable mechanisms for movement to an end position, a pin restoring member relatively shiftable across said group of settable pins with said key operable pin setting means and said actuators, a manipulative member, a linkage operable by said manipulative member and connected to said pin restoring member in said end position of said relatively shiftable mechanisms, to shift said pin resetting member to an ineffective position and a lock for said re-indexing key, said lock releasable by said manipulative member in its pin restoring member disabling position.

11. In a machine of the class described having a plurality of numeral keys, a group of settable pins, mechanisms, comprising a plurality of actuators and key operable pin setting means, shiftable relatively to said group of settable pins and urged in one direction of relative motion, escapement mechanism to restrain said relatively shiftable mechanisms, said escapement mechanism operable by said keys to enable a one step relative movement of said shiftable mechanisms, a re-indexing key, mechanism operable by said re-indexing key to render said escapement mechanism ineffective and thereby free said relatively shiftable mechanisms for movement to an end position, a pin restoring member relatively shiftable across said group of settable pins with said key operable pin setting means and said actuators, a manipulative member, a linkage operable by said manipulative member and connected to said pin restoring member in said end position of said shiftable mechanisms, to shift said pin resetting member to an ineffective position, a latch for said manipulative member, said latch releasable by said shiftable mechanisms in the final position, and a lock for said re-indexing key, said lock moved out of latching position by said manipulative member upon movement to shift said pin resetting member to said ineffective position.

12. In a machine of the class described having a group of numeral keys, a field of settable pins, a plurality of register actuators, a plurality of pin setting linkages, one from each key to an associated row of pins, said actuators and said pin setting linkages being relatively shiftable with respect to said pins to set said pins seriatim to represent a multi-denominational value, a pin restoring member shiftable with respect to said pins, and an escapement mechanism operable by said keys to permit step by step shifting of said relatively shiftable pins, actuators, linkages and pin restoring member, the combination of a manipulative member, means connected to said pin restoring member in the end shifted position of said pin restoring member with respect to said field of pins and operable by said manipulative member to shift said pin restoring member to an

ineffective position, a latch for said manipulative member and means operable in said end position of said relatively shiftable linkages and pins to release said latch.

- 5 13. In a machine of the class described having a group of numeral keys, a field of settable pins, mechanisms relatively shiftable with respect to said pins to set said pins seriatim to represent a multi-denominational value, said 10 relatively shiftable mechanisms comprising a plurality of actuators, a plurality of pin setting members actuatable by said keys and a pin restoring member, and an escapement mechanism operable by said keys to permit step by step shifting of said relatively shiftable mechanisms, the combination of a manipulative member, means connected to said pin restoring member in the final shifted position of said pin restoring member with respect to said field of pins and operable by said manipulative member to shift said pin restoring member to an ineffective position, a latch for said manipulative member, means operable in the final position of said relatively shiftable mechanisms to release said latch, a re-indexing key, means controlled by said re-indexing key for releasing said escapement mechanism to permit movement of said relatively shiftable mechanisms to the end position, and means settable by said manipulative member in the 15 position retaining said pin restoring member effective to prevent operation of said re-indexing key.
- 20 14. In a machine of the class described, having a set of numeral keys, a group of settable pins, key operable members shiftable across said pins to enable operation of said keys to set said pins to represent a multi-digit number, a pin restoring bar and a plurality of register actuators shiftable with said key operable members and an escapement mechanism operable by said keys for enabling step by step shifting of said key operable members, said restoring bar and said actuators, the combination of a manipulative member, means operable by said manipulative member and engageable by said pin restoring bar in an end shifted position of said bar to move said pin restoring bar to an ineffective position, a re-indexing key, means normally retained by said re-indexing key and releasable thereby to disable said escapement mechanism and thereby 25 permit movement of said key operable means and said pin restoring bar to the end shifted position, said means settable by said manipulative member to engage a part of said re-indexing key to prevent operation of said re-indexing key when 30 said pin restoring bar is in the effective position.
